Primary Examiner — Derrick E Holland**CLAIM**

The ornamental design for a solar module, as shown and described.

DESCRIPTION

FIG. 1 is a top perspective view of a solar module, showing our new design;

FIG. 2 is a top plan view thereof;

FIG. 3 is a left side elevation view thereof;

FIG. 4 is a right side elevation view thereof;

FIG. 5 is a front elevation view thereof;

FIG. 6 is a back elevation view thereof; and,

FIG. 7 is a bottom plan view thereof.
